UNITED STATES PATENT OFFICE.

ORVILLE B. HIGDON, OF WATERLOO, IOWA.

CARD-INDEXING DEVICE.

1,359,990.

Specification of Letters Patent. Patented Nov. 23, 1920.

Application filed February 19, 1920. Serial No. 359,995.

To all whom it may concern:

Be it known that I, ORVILLE B. HIGDON, a citizen of the United States of America, and a resident of Waterloo, Blackhawk county, 5 Iowa, have invented certain new and useful Improvements in Card-Indexing Devices, of which the following is a specification.

My invention relates to improvements in card-indexing devices, and the object of my 10 improvement is to supply in such devices for serially grouped and longitudinally approximated or partially overlaid cards, means for holding them flatly together, and also adapted to operate under certain conditions of actuation to support the cards in an 15 upright position, loosely, for easy insertion or removal.

This invention also constitutes an improvement upon my card-indexing device 20 patented August 21, 1917, No. 1,237,336.

The object referred to is accomplished by the means which are hereinafter described and claimed, and which are illustrated in the accompanying drawings, in which Fig- 25 ure 1 is a plan view of a cabinet-drawer comprising and containing my improved card-indexing device; Figs. 2, 3 and 4 are respectively vertical longitudinal sections of the device, taken on the broken lines 2—2, 30 3—3, and 4—4. Fig. 5 is a vertical longitudinal section of the device with the card-containing drawer and its moving parts in open and expanded positions, and taken on the broken line 2—2 of Fig. 1, looking in the direction indicated by the arrow. Fig. 6 is an 35 enlarged detail view of a portion of the open end of the compartment in the cabinet which receives the card-indexing drawer, and showing a part of the latter seated 40 therein. Fig. 7 is a full size view of one face of a tabbed card such as is used in said device.

Similar numerals of reference denote corresponding parts throughout the several 45 views.

1 is a cabinet compartment with open front end, and contains adjacent its inner side walls upright track-rails 5 which form part of a longitudinally split tubular structure of which an upright part 3 is secured, 50 as by spot-welding, to said inner wall, while its upper part 4 is spaced from, extends over, or overhangs the rail part 5 to serve as a guard or stop-member. Immediately below the part 3 of said tubular structure, in each case, an angular hook 6 with inwardly

bent end is pivotally mounted in a space 18 between the compartment bottom 2 and its side-wall.

10 is a cross-plate structure, each end of 60 which has a downwardly channelled rim 8 which may be slidably mounted on one of the rails 5 under the impending stop 4. Longitudinally arranged arms 16 are fixed on said structure near each channel 8 and 65 extend forwardly a distance therefrom.

The numeral 11 denotes a tray or flat carrier-body, whose rear end is bent upwardly, scrolled, and hinged on a cross-rod or pintle 17 whose ends are mounted in openings in 70 said arms 16. The forward end of the tray 11 is bent upwardly at a right angle to serve as a closure for the compartment 1, when the tray is closed thereinto. On the middle of the forward face of this raised part of 75 the tray is a handle 30.

Referring now to Figs. 2 to 5 inclusive, the numeral 20 denotes a pair of side-bars positioned above the tray 11 near its side edges, spaced apart and parallel, and a plurality of similar bars are positioned at equal intervals between these side-bars, parallel therewith, all the bars being of the same length. These bars all have transversely aligned pluralities of holes which are traversed by cross-rods 23, the latter being parallel, and the bars have horizontal ledges 28 below said rods.

The rods 20 with their ledges 28 and said plurality of cross-wires or rods 23 are rigidly connected and thus form a supporting 90 rack for pluralities of overlapping cards 27.

For the purpose of illustration, I have shown a full-size card 27 in Fig. 7. The upper part of the card has side extensions 29 95 which, when the body of the card is inserted between two of the wires 23, rest upon the ledges 28.

Longitudinal bars 12 are fixed on the top 100 of the tray 11 spaced from the side edges of the latter, said side edges being raised and then bent horizontally so that the horizontal parts which are aligned with the channels 8 of the body 10 can be supported slidably upon the tracks 5 when within the compartment 1. The numerals 22 and 24 denote cross-plates whose upper edges are respectively pivoted at 21 and 25 to the forward and rear extremities of the outer rack-bars 20. The lower ends of the plates 22 and 24 110 are pivoted on cross-rods 19 connected between said raised bars 12. As the plates 22

and 24 are of the same width, when they are swung up or down, said card rack is kept parallel with the tray 11.

Connecting rods 13 have their rear ends 5 pivoted at 15 to the forward extremities of the arms 16 and their forward ends are both pivotally and slidably connected to the forward parts of the raised bars or ribs 12 by pintles 14 inserted into longitudinal 10 slots 26 in the latter, the rods 13 being downwardly troughed to ride upon said ribs 12.

The pintle 15 which pivotally connects the rod 13 and the arm 16 in each case, extends from the adjacent rack-bar 20. Because of 15 this connection, when the tray 11 is in a horizontal position, as shown in Figs. 2 to 4 inclusive, the rack is collapsed upon the tray and the cards 27 are compressed in their overlapped relation closely between the 20 cross-wires 23 and the upper surface of the tray so that the whole assemblage of these parts occupy but little space vertically and may be moved into or out of the compartment 1 without interference and so that the 25 upper parts of the cards are plainly visible for reference.

Referring to said Fig. 5, it will be seen that when the tray is fully withdrawn from the compartment 1, the body 10 remaining 30 in the compartment, and the tray is allowed to swing downwardly obliquely to the limit of its downward movement, the connecting rods 13 act to shift the rack members 20 upwardly, releasing the cards 27 so that the 35 latter hang on their tabs or shoulders 29 on the ledges 28 loosely for easy removal or reinsertion.

The hooks 6 are swung upwardly when the tray is withdrawn, to engage end parts 40 8 of the body 10 and hold it within the compartment 1.

Having described my invention, what I claim as new and desire to secure by Letters Patent, is:

1. In a device of the character described, 45 the combination with a channeled compartment, of a mating channeled body, slidably and removably mounted therein, a tray pivotally connected to said channeled body, and a transversely-slotted card-receiving 50 grid pivotally connected at its forward and rear ends to said tray, and pivoted at its rear end to a fixed support to become spread apart from said tray in parallelism when the tray is removed from said compartment and swung downwardly on its 55 pivotal connection to said channeled body.

2. In a device of the character described, an open end channeled compartment, a mating channeled body slidably and removably 60 mounted therein, a tray pivotally connected to said channeled body, and a card-rack pivotally connected at its forward and rear ends to said tray and pivoted at its rear end to said channeled body to swing away 65 from said tray when the tray is removed from the compartment to hang angularly downward on its pivotal connection to said channeled body, said rack comprising a plurality of supports adapted to receive 70 cards removably whereby the latter have their upper edges successively exposed in overlapping relation, and said supports being adapted to compress the cards flatly together when the tray is lifted, with its said 75 pivotal connections to the rack collapsed, to permit the tray, rack and cards to enter said compartment without interference.

Signed at Waterloo, Iowa, this 4th day of Feb., 1920,

ORVILLE B. HIGDON.
